UNITED STATES PATENT OFFICE

2,438,748

SHOE TREE

Edward H. Greenberg, St. Louis, Mo.

Application November 19, 1946, Serial No. 710,804

1 Claim. (CL 12—128.6)

1

This invention relates to new and useful improvements and structural refinements in shoe trees, and the principal object of the invention is to provide a device of the character herein described which may be effectively employed with various types of shoes, such as high heeled shoes, toeless shoes, heel-less shoes, sandals and the like.

A further object of the invention is to provide a shoe tree which may be readily applied to and removed from the shoe and which is easily adjustable so as to accommodate shoes of various sizes.

Another object of the invention is to provide a shoe tree which is simple in construction and which will readily lend itself to economical manufacture.

With the above more important objects in view, and such other objects as may become apparent as this specification proceeds, the invention consists essentially of the arrangement and construction of parts as illustrated in the accompanying drawings, in which:

Figure 1 is a top plan view of the invention.

Figure 2 is a side elevation thereof, partially broken away to reveal its construction.

Figure 3 is a fragmentary perspective detail, and

Figure 4 is a front view of the same.

Like characters of reference are used to designate like parts in the specification and throughout the several views.

Referring now to the accompanying drawings in detail, the invention consists of a shoe tree designated generally by the reference character 10, the same embodying in its construction a hollow toe cap 11, configurated substantially as shown and provided on the upper surface of its lower wall 12 with a pair of spaced parallel guides 13.

The guides 13 form a channel therebetween, and one end portion 14 of an extension arm 15 is slidably receivable in said channel, as will be clearly understood. The end portion 14 is provided in the upper surface thereof with a longitudinally extending recess 16 and the bottom of this recess is, in turn, formed with a longitudinal slot 17.

The bottom wall 12 of the toe cap 11 is formed with a countersink 18 to receive a suitable screw 19, the shank of the latter extending through the slot 17 and engaging a nut 20 slidably positioned in the recess 16.

The aforementioned extension arm 15 is of a substantially diamond-shaped cross sectional configuration and is angulated upwardly as at 21 to provide an upraised arcuate, handle 22. The free end portion of the arm 15 is downturned and

2

forms an arcuate heel-piece 23 which, in turn, terminates in a cylindrical extremity 24.

When the invention is placed in use, the toe cap 11 and the heel-piece 23 are inserted in the respective corresponding portions of the shoe, as will be clearly understood.

The shoe tree may, of course, be readily adjusted to accommodate shoes of various sizes, this being accomplished by simply loosening of the screw 19 and sliding the arm portion 14 between the guides 13 as required. After the necessary adjustment has been made, the screw 19 is, of course, retightened. It will be also observed that the shoe tree, together with the associated shoe, may be conveniently carried by simply grasping the handle portion 22.

It is believed that the advantages and use of the invention will be clearly understood from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

30 A shoe tree comprising in combination, a hollow toe cap, a pair of spaced parallel guides forming a channel in said cap, an extension arm, the forward end portion of said arm being slidable in said channel and being formed with a longitudinal slot, the mid-portion of said arm being arcuated and constituting an upraised handle, the remaining end portion of said arm being downturned and terminating in an arcuate heel-piece, and a clamping bolt provided on said cap and extending through said slot, whereby said arm and said cap are adjustably connected together.

EDWARD H. GREENBERG.
